FIG. 7

FIG. 1 is a top plan view of a photographic film processor or similar article showing by new design;

FIG. 2 is a front elevational view of FIG. 1;

FIG. 3 is a left side elevational view of FIG. 1;

FIG. 4 is a right side elevational view of FIG. 1;

FIG. 5 is a rear elevational view of FIG. 1;

FIG. 6 is a bottom view of FIG. 1; and

FIG. 7 is a front perspective view of FIG. 1.

The dominant features of my design are shown in solid lines in the drawings. The broken line showing of a wire print receptacle in FIG. 7 is for illustrative purposes only, and has been omitted from the other figures for convenience in illustration.

I claim:

The ornamental design for a photographic film processor or similar article, as shown and described.
